SHOE BOTTOM PRESSING MACHINE

Karl Engel, Swampscoot, and Charles S. Kinney,
Middleton, Mass., assignors to United Shoe Ma-
chinery Corporation, Paterson, N. J., a corpo-
ration of New Jersey

Application October 22, 1937, Serial No. 170,432

17 Claims. (Cl. 12—51)

This invention relates to machines for pressing the bottoms of shoes, and in some aspects more particularly to means for applying pressure and heat to the lasted margin of an upper overlying an insole preparatory to the application of an outsole to the shoe. The invention is herein illustrated by reference to the manufacture of shoes in which the upper along the sides of the forepart and around the toe end is secured in lasted position by an adhesive, although it is to be understood that the invention is not thus limited in its applicability.

For the purposes in view, the invention provides a novel construction and arrangement of means for applying pressure to the marginal portion of an upper extending inwardly over an insole in substantially parallel relation to the shoe bottom, the construction shown comprising a device having different shoe pressing members arranged to engage the lasted margin of the upper all around the forepart of a shoe, the different pressing members being heated and being also shaped to conform substantially to the contour of the bottom of the shoe both lengthwise and widthwise of the shoe to adapt them to receive a shoe placed thereon bottom downward. As herein illustrated, the shoe pressing members comprise plates of flexible resilient metal arranged to engage the lasted margin of the upper along the opposite sides of the forepart and an end plate of resilient metal slidably mounted on the side plates and arranged to engage the lasted margin of the upper at the toe end, the metal plates being arranged to bend and conform themselves more closely to the contour of the shoe in response to pressure of the shoe upon them. For controlling the metal plates so as to apply firm pressure to the shoe there are provided, in accordance with a further feature, a plurality of blocks for backing-up the metal plates, the blocks being arranged to adjust themselves in accordance with the contour of the shoe and then to support the metal plates against further bending in response to pressure of the shoe on the plates. As further herein illustrated, the pressing device is movable in response to pressure of the shoe thereon, and in accordance with another feature of the invention, there is provided mechanism operative in response to the movement of the pressing device for moving the shoe pressing members inwardly over the bottom of the shoe in wiping engagement with the upper, this mechanism, as herein shown, comprising parts movable with the pressing device and other parts normally held against movement with the pressing device,

the last-named parts being adjustable relatively to the pressing device to vary the initial positions of the shoe-pressing members to accommodate shoes of different sizes. For pressing the shoe against the pressing device there is provided a toe rest arranged to engage the top of the forepart of the shoe and movable to force the shoe against the pressing device, and in order that the pressure of the shoe-pressing members on the upper will be progressively increased during their inward movements to insure that the lasted margin of the upper will be pressed smoothly and evenly on the insole, spring means is provided against the increasing resistance of which the pressing device is movable. As the pressing members move inwardly over the bottom of the shoe they tend to draw the upper more tightly inward over the insole, thus obviating any tendency for the upper to bulge at the edge of the insole, and in order to render them more effective for this purpose, the pressing members for engaging the lasted margin of the upper along the opposite sides of the forepart have their upper-engaging faces provided with a plurality of projecting edges or burrs. Preferably also, and as herein shown, there is provided means for locking the toe rest in position to maintain the pressure on the shoe as long as desired after the shoe pressing members have been moved inwardly over the bottom of the shoe.

The above and other features of the invention, including various novel details of construction and combinations of parts, will now be more particularly described by reference to the accompanying drawings and pointed out in the claims.

In the drawings,

Fig. 1 is a view in side elevation of a machine in which the invention is embodied, with parts broken away and parts in section;

Fig. 2 is a plan view on an enlarged scale of the shoe-pressing means and parts associated therewith;

Fig. 3 is a view partly in front elevation and partly in section of the shoe-pressing means and associated parts;

Fig. 4 is a view similar to a portion of Fig. 3, but illustrating the positions of the parts with a shoe under pressure in the machine;

Fig. 5 shows the shoe-pressing means partly in left-hand side elevation and partly in section, with the parts in the positions shown in Fig. 4;

Fig. 6 is a transverse vertical section through a portion of the machine and a shoe, illustrating

the positions of the parts before any substantial amount of pressure is applied to the shoe; and

Fig. 7 is a view similar to Fig. 6, but illustrating the positions of the parts at the end of the pressing 5 operation.

The illustrated machine comprises a base 10 (Fig. 1) for supporting a casting 12 which is bored to receive vertical rods 14 depending from a plate 16 on which is mounted a device for 10 pressing or ironing the margin of the lasted upper around the forepart of the shoe. The plate 16 is supported by springs 18 which surround the rods 14 between the plate and shoulders 20 formed within recesses 22 in the casting 12 and 15 by a spring 24 which presses upwardly against the intermediate portion of the plate and at its lower end engages a shoulder 26 within a recess 28 in the casting 12 (Fig. 5). Initially the springs 18 and 24 are under slight tension and act to 20 hold the plate 16 in spaced relation to the casting 12 determined by the engagement of collar-headed screws 30 (Fig. 2) with the upper surface 32 of the plate, the screws 30 extending through the plate and being threaded into the casting 12.

25 The shoe bottom pressing and ironing device comprises a pair of flexible resilient metal plates 34 (Figs. 2, 3 and 4) which are shaped to conform substantially to the contour of the bottom of a shoe both lengthwise and widthwise of the shoe 30 and are arranged to engage the margin of the lasted upper at the 35 end of the toe (Figs. 2 and 5). The outer margin of each side plate 34 is clamped to a holder 38 (Figs. 3 and 4) having formed on its opposite ends trunnions 40 connected by links 42 to links 44 that are pivotally connected to bosses 46 on a 40 rectangular-shaped hollow casting 48 which is fastened to the plate 16 by screws 50 (Fig. 5) and over which extend the ironing plates 34, 36. Each pair of links 42, 44 is pivotally connected together and to one link 52 of a toggle, the other 45 link 54 of which toggle is pivotally connected at 56 to a bracket 58 secured to the plate 16 by a screw 60. The links 52, 54 of each toggle are held normally in non-parallel relation, with a roll 62 carried by a downwardly extending portion 64 50 on the link 54 in engagement with an adjustable abutment, illustrated as a short rod 66 extending upwardly through a recess 68 in the plate 16, by means of a spring 70, one end of which is connected to the link 54 and the other end of which is 55 connected to a pin 72 in the plate 16 (Fig. 3). Each rod 66 is slidably mounted in a vertical bore 74 (Fig. 1) in the casting 12 and threaded into the lower end portions of the rods 66 are adjustable screws 76 arranged to engage inclined surfaces 60 78 formed on a pair of parallel bars 80 slidably mounted in horizontal guideways in the casting 12. The bars 80 are connected together by a cross piece 82 and extending through the cross piece is a screw 84 threaded in the casting 12. Fast to 65 the outer end of the screw 84 is a small hand-wheel 86 for turning it, the screw being held against endwise movement relative to the cross piece by means of a collar 88 on the hand wheel and a collar 90 formed on the screw, the collars 70 88 and 90 engaging opposite side faces of the cross piece. From the above description it will be evident that by turning the screw 84 the flexible plates 34 may be adjusted toward or from each other laterally of the shoe to vary their 75 initial positions as may be necessary in operating

upon shoes of different sizes. To assist in supporting and guiding the holders 38 for movements toward or from each other laterally of the shoe, there is secured to each holder by a screw 92 a bar 94 the lower end portion of which is provided with a substantially horizontal bore to receive a shouldered screw 96 threaded into the plate 16. 5

In the illustrated construction, the end plate 36 for engaging the margin of the lasted upper at the toe end is arranged to overlie the side plates 10 34 and is secured by a clamp 98 to a holder 100 (Figs. 2 and 5) pivotally connected to the upwardly extending arm 102 of a bell-crank lever 104 which is pivotally connected at 106 to a bracket 108 fastened to the plate 16 by screws 110 (Fig. 2). The bell-crank lever 104 has a pair of rearwardly extending arms 112 which straddle an upwardly extending rib 114 on the casting 12 and are arranged to engage adjustable abutments 116 one on each side of the rib 114. The holder 100 has a rearwardly projecting portion 118, and engaging a shoulder within a recess 122 in the portion 118 of the holder is one end of a spring 124 the opposite end of which engages a shoulder within a recess 128 in one of the rearwardly extending arms 112 of the bell-crank lever 104, the spring 124 acting to swing the bell-crank lever and the holder 100 in opposite directions to hold the arms 112 of the bell-crank lever in engagement with the abutments 116 and to press the plate 36 against the plates 34. Each abutment 116 has formed therein an elongated slot 130 and extending through the slots 130 and a bore 132 in the rib 114 is a bolt 134 for clamping the abutments in adjusted position. It will be 35 evident that the initial position of the end plate 36 lengthwise of the shoe to accommodate shoes of different sizes may be varied by loosening the bolt 134 and moving the abutments 116 heightwise of the shoe. 40

In the illustrated machine the shoe-pressing device is arranged to receive a shoe placed initially thereon bottom downward, after which the shoe is forced downwardly to cause the pressing device to apply pressure to the bottom of the 45 shoe by means of a toe rest 136 (Figs. 1 and 3) which is arranged to engage the top of the forepart of the shoe. The toe rest comprises a felt pad 138 preferably molded to conform approximately to the lateral contour of the top of the 50 forepart of the shoe. The pad 138 is adhesively secured to a block 140 formed on the end of a post 142 slidably mounted for movements toward and from the shoe-pressing device in a bracket 143 secured by screws 144 to a crosshead 146 adjustably secured to the upper ends of a pair of vertical bars 147 which are slidably mounted in guideways 148 (Fig. 2) in the casting 12. Threaded into the post 142 is a rod 150 provided with a reduced end portion 152 which extends through the crossbar 60 154 of an inverted substantially U-shaped bracket 156 fastened to the bracket 143 by screws 158. Fast to the upper end of the rod 150 is a handle 160 for turning the rod, the rod being held against endwise movement relatively to the 65 bracket 156 by the handle 160 and a collar 162 pinned to the rod. For holding the post 142 against turning movement in the bracket 143 there is provided a screw 164 threaded into the bracket and having a reduced end portion 166 70 (Fig. 5) extending into a lengthwise slot 168 in the post. It will be understood that by movement of the handle 160 the toe rest 136 may be adjusted heightwise of the shoe relatively to the shoe-pressing device. The vertical bars 147 are 75

connected at their lower ends by a crosspiece 170 to which there is pivotally connected one end of an adjustable rod 172 pivotally connected at its opposite end to a treadle 174 fulcrumed at 176 to 5 the frame 10. The treadle 174 is normally held in upraised position in engagement with a stop 178 by springs 180, one on each side of the machine, each spring being connected at its upper end to a pin 182 in the casting 12 and at its 10 lower end to a pin 184 projecting from the end of the crosspiece 170. For locking the treadle in depressed position there is provided a spring-operated latch 186 arranged to engage a finished surface 187 on the treadle 174. To release the 15 treadle 174 for upward movement there is provided an auxiliary treadle 188 pivotally connected to the treadle 174 and having a forwardly extending portion 190 arranged upon depression of the auxiliary treadle to move the latch 186 against 20 the resistance of its operating spring out of engagement with the treadle 174.

When the shoe is forced downwardly against the metal plates 34, 36, the plates bend and conform themselves more closely to the contour of 25 the bottom of the shoe, and in order that more effective pressure will be applied to the shoe by the plates 34, 36 there are arranged within a recess 192 (Fig. 2) in the hollow casting 48 a plurality of blocks 194 for engaging those portions 30 of the plates that extend inwardly over the bottom of the shoe. The blocks 194, illustrated as four in number, are confined by the walls 196, 198 of the recess 192 and each block is provided with a tapered recess 200 terminating in a semi-spherical seat 202. Engaging this seat is the 35 rounded upper end of a pin 204, the opposite rounded end of which engages a similarly shaped seat 206 in the plate 16. The pins 204 are held against excessive tipping movement relatively to 40 the plate 16 by small plates 208 fastened to the plate 16 by screws 210, each plate having formed therein a tapered hole 212 through which the pin 204 extends, the hole 212 being in alignment with the seat 206. The blocks 194 are thus free to tip 45 relatively to each other and the plate 16 in directions both lengthwise and widthwise of the shoe to adjust themselves to the contour of the shoe bottom with the plates 34, 36, after which they act to support the plates against further bending 50 in the pressing operation. Preferably, the upper surfaces of the blocks 194 are shaped to conform substantially to the contours of those portions of the ironing plates 34 engaged by the blocks and preferably also the blocks are heated to maintain 55 the ironing plates in a heated condition. For heating each block 194 there is provided an electrical heating unit 214 which extends into the block and is connected by electrical conductors 216 to any convenient source of electrical energy 60 for heating the unit.

As previously pointed out, the plate 16 on which the pressing or ironing unit is mounted is supported initially in spaced relation to the casting 12 by springs 18 and 24. With the plate 16 thus upheld the holders 38 and the side plates 34 are held in their outermost positions by the springs 70 which act to hold the toggle links 52, 54 in non-parallel relation, the holder 100 and the end plate 36 being also held in their outermost positions by the spring 124 which acts to hold the arms 112 of the bell-crank lever 104 in engagement with the abutments 116. As thus positioned, the ironing plates 34, 36 are arranged to engage the overlasted marginal portion of the upper 75 around the forepart of a shoe placed initially

thereon bottom downward. It will be understood that before a shoe is presented to the machine the forepart of the shoe will have been previously lasted, the upper being preferably fastened to the insole by an adhesive. If desired also the upper overlying the insole may be moistened to assist in smoothing it free from wrinkles by the inwardly moving heated plates 34, 36 of the machine. With the shoe positioned properly on the plates 34, 36, the operator depresses the treadle 174 to force the shoe, through the action of the toe rest 136, against the plates. In response to the pressure of the shoe upon them, the plates 34, 36 are flexed to conform more closely to the contour of the shoe bottom and the blocks 194 15 tip relatively to each other and to their supporting pins 204 until they have adjusted themselves to the contour of the bottom of the shoe with the plates 34, 36. Thereafter, in the continued downward movement of the treadle the plates 34, 36 are 20 supported against further bending by the blocks 194 and the pressing or ironing device is moved downwardly with the shoe against the resistance of the springs 18 and 24 until the plate 16 engages an adjustable stop illustrated as a screw 25 218 threaded into the casting 12 (Fig. 5). As the pressing or ironing device is depressed, the toggle links 52, 54 are swung into substantially parallel relation in response to the relative movement of the plate 16 and the rods 66, and the bell-crank 30 lever 104 is swung in a clockwise direction (Fig. 5) by the engagement of its arms 112 with the abutments 116. As the toggle links 52, 54 are thus swung into parallel relation and the bell-crank lever 104 is swung in a clockwise direction the 35 plates 34 and 36 are forced inwardly over the shoe bottom in wiping engagement with the marginal portion of the upper. It will be understood that the downward movement of the pressing or ironing device occurs only after the pressure of 40 the shoe upon the plates 34 and 36 is great enough to overcome the resistance of the springs 18 and 24 which are further compressed as the plates 34 and 36 are moved inwardly over the bottom of the shoe in wiping engagement with the upper. 45 The margin of the upper around the forepart is therefore subjected to progressively increasing pressure and heat to flatten it upon the insole and to smooth it free from wrinkles. As the shoe-pressing members or plates 34, 36 move inwardly over the bottom of the shoe they tend to draw the upper around the entire forepart of the shoe inward over the insole, thus obviating any tendency for the upper to bulge at the edge of the insole in response to the pressure applied, 55 and in order to render the plates 34 more effective for this purpose the upper engaging face of each plate 34 is provided with a plurality of projecting edges or burrs 220 formed by punching holes 222 in the plate (Figs. 6 and 7). With the 60 plate 16 in engagement with the adjustable stop 218, the toe rest 136 and the bars 147 are locked against upward movement by the engagement of the latch 186 with the finished surface 188 on the treadle 174, to permit the shoe to be subjected to pressure and heat as long as desired without the necessity for the operator to hold the treadle depressed. To release the shoe, the operator depresses the auxiliary treadle 188, whereupon the bars 147 and the toe rest 136 are moved 65 upwardly by the springs 180, and the pressing or ironing device is moved upwardly by the springs 18 and 24 until the plate 16 engages the screws 30. As the pressing device moves upwardly the springs 70 act to swing the toggle links 52, 54 75

into non-parallel relation to move the plates 34 outwardly to their initial positions, the end plate 36 being moved outwardly to its initial position by the action of the spring 124 on the bell-crank 5 lever 104.

Having described the invention, what we claim as new and desire to secure by Letters Patent of the United States is:

1. In a machine for pressing the bottoms of 10 shoes, a device for applying pressure and heat to the bottom of the lasted forepart of a shoe before an outsole is applied to the shoe, said device comprising different heated shoe pressing members arranged to engage the lasted margin 15 of the upper at the opposite sides of the shoe, means for pressing the shoe upon said device, said pressing device being movable rectilinearly in response to pressure of the shoe thereon, and means operative in response to such movement 20 of the pressing device for imparting to said shoe-pressing members movements inwardly over the bottom of the shoe in wiping engagement with the margin of the upper.

2. In a machine for pressing the bottoms of 25 shoes, a device for applying pressure and heat to the bottom of the lasted forepart of a shoe before an outsole is applied to the shoe, said device comprising heated shoe-pressing members arranged to engage the lasted margin of the 30 upper all around the forepart of the shoe, means for pressing the shoe upon said device, said pressing device being movable rectilinearly in response to pressure of the shoe thereon, mechanism operative in response to the movement of said device for moving said shoe-pressing members inwardly over the bottom of the shoe in wiping engagement with the margin of the upper, and spring means engaging said rectilinearly movable device for progressively increasing the pressure 35 of said shoe-pressing members on the upper during their inward movements.

3. In a machine for pressing the bottoms of 40 shoes, a device for applying pressure to the bottom of the lasted forepart of a shoe before an outsole is applied to the shoe, said device comprising shoe-pressing members for engaging the lasted margin of the upper all around the forepart of the shoe, a toe rest arranged to engage the top of the forepart of the shoe and movable to press the shoe against said device, said device being yieldingly movable in response to pressure of the shoe thereon, mechanism operative in response to movement of the device for moving said shoe-pressing members inwardly over the 45 bottom of the shoe in wiping engagement with the margin of the upper, and means for locking the toe rest in position to maintain the pressure on the shoe after said shoe-pressing members have been moved inwardly over the bottom of the 50 shoe.

4. In a machine for pressing the bottoms of 55 shoes, a device for applying pressure and heat to the bottom of a lasted shoe before an outsole is applied to the shoe, said device comprising shoe-pressing members arranged to engage the lasted margin of the upper at the opposite sides of the shoe, means for pressing the shoe upon said device, said device as a whole being movable in response to pressure of the shoe thereon, 60 and mechanism controlled by the movement of said device for imparting to said shoe-pressing members movements relatively to other portions of the device in directions to draw the upper inwardly over the bottom of the shoe, said shoe- 65 pressing members having their upper engaging

faces provided with a plurality of projecting edges to render them more effective to tighten the upper inwardly over the edge of the shoe bottom.

5. In a machine for pressing the bottoms of 70 shoes, a device for applying pressure to the bottom of a lasted shoe before an outsole is applied to the shoe, said device comprising shoe-pressing members for engaging the lasted margin of the upper at the opposite sides of the shoe, a toe rest arranged to engage the top of the forepart of the 75 shoe and movable to press the shoe against said members, a support for said shoe-pressing members movable with said toe rest in response to pressure of the shoe upon said members, spring means against the resistance of which the support is thus movable, and mechanism for moving said pressing members inwardly over the bottom of the shoe relatively to said support in wiping engagement with the upper in response to the movement of said support. 80

6. In a machine for pressing the bottoms of 85 shoes, a device for applying pressure to the bottom of a lasted shoe before an outsole is applied to the shoe, said device comprising shoe-pressing members arranged to engage the lasted margin 90 of the upper along the opposite sides of the forepart and a pressing member for engaging the lasted margin of the upper at the toe end, a common support for said pressing members yieldingly movable in response to pressure of the shoe on said members, mechanism operative in response to the movement of said support for moving said side-pressing members relatively to the support inwardly over the bottom of the shoe, and additional mechanism operative in response to the movement of the support for moving the end-pressing member inwardly over the bottom 95 of the shoe with the side members. 100

7. In a machine for pressing the bottoms of 105 shoes, a device for applying pressure to the bottom of a lasted shoe before an outsole is applied to the shoe, said device comprising different shoe-pressing members arranged to support a shoe presented by the operator bottom downward by engagement with the lasted margin of 110 the upper along the sides of the forepart, means arranged to force the shoe against said pressing members, a support for said pressing members yieldingly movable in response to pressure of the shoe on said members, and mechanism operative 115 in response to the movement of said support for moving said pressing members inwardly over the bottom of the shoe in wiping engagement with the upper, said mechanism comprising parts 120 movable with said support and cooperating parts normally held against movement with the support, said last-named parts being movable relatively to the support to adjust the pressing members lengthwise and laterally of the shoe to accommodate shoes of different sizes. 125

8. In a machine for pressing the bottoms of 130 shoes, a device for applying pressure to the bottom of a lasted shoe before an outsole is applied to the shoe, said device comprising shoe-pressing members arranged to engage the lasted margin of the upper along the opposite sides of the forepart of the shoe, a support for said pressing members movable heightwise of the shoe in response to pressure of the shoe on said pressing members, and means operated by such movement of the support for moving the pressing members toward each other laterally of the shoe, said means comprising different pairs of toggle links connecting said pressing members and the support and members normally held against move- 135 75

ment with the support for engaging and swinging said different pairs of toggle links into substantially parallel relation.

9. In a machine for pressing the bottoms of 5 shoes, a device for applying pressure to the bottom of a lasted shoe before an outsole is applied to the shoe comprising shoe-pressing members arranged to engage the lasted margin of the upper along the opposite sides of the forepart of the 10 shoe, a support for said pressing members movable heightwise of the shoe in response to pressure of the shoe on said pressing members, mechanism operative in response to such movement of the support for moving the pressing members 15 toward each other laterally of the shoe comprising different pairs of toggle links connecting said pressing members and the support and abutments normally held against movement with the support for swinging said toggle links in directions to impart to said pressing members their 20 movements toward each other, and means for adjusting said abutments relatively to said support to vary the initial positions of said pressing members to accommodate shoes of different sizes.

25 10. In a machine for pressing the bottoms of shoes, a device for applying pressure and heat to the bottom of a lasted shoe before an outsole is applied to the shoe, said device comprising heated plates of flexible resilient metal shaped to 30 conform substantially to the contour of the bottom of a shoe and arranged to support a shoe placed thereon bottom downward by engagement with the lasted margin of the upper all around the forepart of the shoe, means arranged to engage the top of the forepart of the shoe and movable to press the shoe against said metal plates, said device being movable in response to pressure of the shoe on said plates, said device including means conformable substantially to the contour 35 of the bottom of the shoe for supporting said metal plates against the pressure of the shoe upon them, and mechanism for forcing said metal plates inwardly over the bottom of the shoe relatively to said conformable means in wiping engagement with the upper in response to the movement of the device.

11. In a machine for pressing the bottoms of 40 shoes, a device for applying pressure and heat to the bottom of a lasted shoe before an outsole is applied to the shoe, said device comprising heated plates of flexible resilient metal for engaging the lasted margin of the upper along the opposite sides of the forepart and a plate of resilient metal slidably mounted on said side plates for 45 engaging the lasted margin of the upper at the toe end, said plates being flexibly conformable to the contour of the bottom of a shoe in response to pressure of the shoe thereon, a support for said plates, a plurality of blocks on said support 50 mounted to tip relatively to one another to adjust themselves in accordance with the contour of the shoe with the plates and thereafter to increase the pressure of the plates on the shoe, means arranged to engage the top of the forepart of the shoe and movable to press the shoe against said plates, said support being yieldingly movable in response to pressure of the shoe on said plates, and mechanism for moving said side plates laterally of the shoe and the end plate 55 lengthwise of the shoe in wiping engagement with the upper in response to the movement of said support.

12. In means for pressing the bottoms of shoes, 60 a pressing device comprising metal plates arranged to engage the bottom of a shoe at the

opposite sides, said plates being flexibly conformable to the contour of the shoe in response to pressure of the shoe thereon, a plurality of blocks backing up said plates and mounted to tip relatively to one another to adjust themselves in accordance with the contour of the shoe and then to support the plates against pressure of the shoe upon them, and means for moving the plates relatively to the blocks inwardly over the bottom of the shoe.

13. A device for pressing the bottoms of shoes, 65 said device comprising metal plates arranged to engage the bottom of a shoe at the opposite sides and flexibly conformable to the contour of the shoe in response to pressure of the shoe thereon, and a plurality of blocks mounted to tip relatively to one another to adjust themselves in accordance with the contour of the bottom of the shoe with said plates and then to increase the pressure of the plates on the shoe.

14. A device for pressing the bottoms of shoes, 70 said device comprising shoe-engaging plates arranged to engage the bottom of a shoe at the opposite sides, said plates being flexibly conformable to the contour of the bottom of the shoe in response to pressure of the shoe thereon and being mounted for movement inwardly over the bottom of the shoe, and a plurality of blocks backing up said plates and mounted to tip relatively to one another to adjust themselves in accordance with the contour of the shoe and then to support said plates against pressure of the shoe upon them.

15. A device for pressing the bottoms of shoes, 75 said device comprising resilient shoe-engaging plates arranged to engage the bottom of a shoe at the opposite sides of the forepart and at the toe end, said plates being flexibly conformable to the contour of the shoe in response to pressure of the shoe upon them and being mounted for movement inwardly over the bottom of the shoe, and a plurality of blocks for backing up said plates, said blocks being mounted to tip in directions both lengthwise and laterally of the shoe to adjust themselves in accordance with the contour of the shoe and arranged then to support said plates against pressure of the shoe upon them.

16. A device for pressing the bottoms of shoes, 80 said device comprising metal plates arranged to engage the bottom of a shoe at the opposite sides and at the end of the forepart, said plates being flexibly conformable to the contour of the shoe in response to pressure of the shoe thereon, and a plurality of blocks backing up said metal plates, said blocks being curved to approximate the contour of the shoe bottom and being mounted to adjust themselves more closely to the contour of the shoe bottom and then to support the metal plates against pressure of the shoe upon them.

17. A device for pressing the bottoms of shoes, 85 said device having metallic shoe-engaging plates at the opposite sides and at the end of the forepart, said plates being conformable to the contour of the bottom of the shoe and being also movable inwardly over the shoe bottom, a plurality of blocks backing up said metallic plates, said blocks being mounted to tip in directions lengthwise and laterally of the shoe to adjust themselves in accordance with the contour of the shoe and arranged then to increase the pressure 90 of the plates on the shoe during their inward movements, and electrical heating means in each of said blocks for heating them.

KARL ENGEL.

CHARLES S. KINNEY. 75
